UNITED STATES PATENT OFFICE.

PETER MC MENAMIN, OF JERSEY CITY, NEW JERSEY.

TICKET-CLASP.

SPECIFICATION forming part of Letters Patent No. 429,148, dated June 3, 1890.

Application filed February 24, 1890. Serial No. 341,511. (No model.)

To all whom it may concern:

Be it known that I, PETER MC MENAMIN, a citizen of the United States, residing at Jersey City, in the county of Hudson and State 5 of New Jersey, have invented certain new and useful Improvements in Railroad - Ticket Holders; and I do hereby declare the following to be a full, clear, and exact description of the invention, such as will enable others 10 skilled in the art to which it appertains to make and use the same.

My invention relates to ticket-holders for railway-passenger tickets.

The object of my invention is to supply the 15 necessity felt by the traveling public of a simple, cheap, and effective device for holding and exposing to the view of the conductor as he passes through the car a railroad ticket or pass and to provide a ticket-holder susceptible of ready attachment to the coat or 20 other wearing-apparel, or to the back or other upholstered portion of a car-seat at a conspicuous point.

It is also my object to provide a collapsible 25 ticket-holder, or one that when not in use can be folded into a small space for convenience in carrying the same in the pocket.

In the drawings, Figure 1 is a front elevation in perspective of my ticket-holder. Fig. 30 2 is a front elevation of my ticket-holder folded; and Fig. 3 is a section taken on the line xx of Fig. 1, showing ticket in position.

Referring to the accompanying drawings, 35 which form part of this specification, A denotes the body portion of my ticket-holder, formed of a sheet-metal strip having a flange c turned up on its upper edge, which, as shown in Fig. 1, is cut or separated at either end from the body A to form dependent springs 40 $c' c'$.

B B' are spring-clasps, formed of narrow sheet-metal strips, pivoted at $b b'$ to the body A. Said clasps B B' are doubled upon themselves or bent to form a loop and spring- 45 tongue, as shown in Fig. 3. The free end of each tongue is bent outwardly in a curvilinear line from their point of contact to form open jaws at d . The strip A and springs $c' c'$ are made of one piece of sheet metal, and 50 may be stamped out and formed up by a suitable die.

As shown in Fig. 1, the clasp B' is pivoted to the body A near the lower edge of the same, while the clasp B is pivoted near the upper edge of said body. This construction allows 55 the clasps to be folded into position without interference, the strip B being first folded in position. The springs $c' c'$ serve to hold the spring-clasps open. They bear upon the inner elongated ends of said clasps when unfolded or opened, as shown in Fig. 1. To hold the clasps closed, the strips forming the same are bent or curved rearwardly, as shown in Fig. 3, and when folded said curved or bent portion acts as a spring to keep the clasps in 60 position on body A. As shown in Fig. 3, this curve or bend in the strips B B' serves also to incline rearwardly the ticket or the part or coupon E of the same in use, thereby affording the conductor a better view and enabling him to inspect, punch, or remove the same with greater ease. The loops formed in the clasps or strips B B' serve to strengthen the tension of the sprung tongue, and the space within the loop serves to accommodate 65 or hold the folded or unused portion of the ticket.

To fasten the ticket-holder to the clothes or upholstered portion of a car-seat, I use an ordinary safety-pin attached to the back of 80 the body A by cutting or stamping out from said body dependent tongues, as shown in Fig. 1, and bending the same to form bearings for the safety-pin, as shown in Fig. 3.

It is evident that my ticket-holder may be 85 used for other articles. For instance, it could be used as a badge-holder for ribbon badges, in which case the body portion could be given a highly-ornamental finish.

Having shown and described my invention, 90 what I claim, and desire to secure by Letters Patent, is—

1. A collapsible ticket-holder provided with two ticket-clamping arms formed of narrow sheet-metal strips doubled upon themselves 95 to form a loop and spring-clamp, said arms being pivoted one to each end of the body portion of the ticket-holder and adapted to be folded in a plane parallel with said body portion, substantially as shown and described. 100

2. A ticket-holder having the body portion consisting of a flanged narrow sheet-metal

strip having dependent springs formed at each end of said flange and provided with ticket-clamping arms pivoted at either end thereof and adapted to be folded inwardly upon said body portion and retained in position thereon open by said springs, substantially as shown and described.

In testimony whereof I affix my signature in presence of two witnesses.

PETER McMENAMIN.

Witnesses:

PETER McCABE,
JAMES ADAMS.
